UNITED STATES PATENT OFFICE.

WILLIAM A. ORENDOFF, OF BLOOMINGTON, ILLINOIS.

GRAIN-DUMPING END GATE FOR GRAIN WAGONS.

Application filed June 28, 1926. Serial No. 119,121.

My invention relates to end gates for grain wagons and particularly to a type of grain wagon that is commonly used for carrying grain to elevators and the like where grain is commonly hauled and dumped into bins; an object being in this device particularly to provide a grain dumping end gate which will not only hold the grain securely when closed but also make it possible to very easily limit the flow of grain from the wagon when dumping the grain into a bin or elevator or the like.

A particular object of my invention is to provide an end gate for grain wagons that may be easily adjusted into operative position and substantially held in such position; and when in operation be conveniently and easily controlled in the normal flow of grain from a grain wagon.

20 A further object of my invention is to provide in an end gate for grain wagons a device that may be economically manufactured and simple to operate.

I attain the object of my invention in the device described in the annexed specification, recited in the claims and illustrated in the accompanying drawing in which like reference numerals indicate like parts in the several figures.

30 Referring to the figures:

Figure 1 is an elevation of the grain control end gate of my invention shown in a closed position.

Figure 2 is an elevation of my end gate shown in an opened position in which position the closure members are held to a position of substantial engagement by a latch member adapted to hold the end gate closure members within predetermined open limits.

Figure 3 is a top view of the end gate shown in the same open position as is illustrated in Figure 2.

Referring in detail to the numerals in the several figures, I provide a latch member —1— pivotally attached to a supporting bracket —2— by a pivot pin —3— supported on a closure member —4— and said latch member —1— is attached to extend across closure member —4— and closure member —5—.

It will be observed that latch member —1— has at each end a stop member designated by numerals —6— and —7— respectively. These two stop members each have

a specific purpose in the normal operation of the end gate which is as follows: Stop member —7— not only provides a bumper for latch —1— when the latch is moving into normally closed position against keeper —8— but it also provides a stop limit when closure members —4— and —5— are opened to an intended limit in which position stop member —7— comes into contact with guide bracket —9— and there stops the opening movement of closure members —4— and —5—.

Stop member —6— is adapted to provide a limiting or bumper member for lock —10—.

At corresponding ends of latch member —1— are integral tongues —11— and —12—, and tongue —11— is adapted to be held snugly by lock member —10— when latch member —1— is in normally closed position while tongue —12— is adapted to slidably move longitudinally across supporting bracket —13— and become engaged by keeper —8— as it moves in behind it when locking closure members —4— and —5—. Numeral —14— indicates the strap about hinge pin —32—.

Plate —15— normally guides tongue —12— behind the keeper —8—. Bracket —2— normally supports latch member —1— on pivot —3— and also pivotally supports lock —10— at pivot —16— while an integral stop member —17— is made to protrude from surface —18— of bracket —2— to an extent that will make it necessary to slidably lift lock member —10— when releasing latch member —1— by pulling on handle —19— of lock member —10— so as to be able to pivotally rotate lock member —10— on point —16— so that the handle —19— thereof slips over the top of protruding knob —17—.

It will be seen, therefore, that when lock member —10— is held in a locked position as is shown in Figure 1, that protruding lug —17— provides a stop member for handle —19— of lock —10— preventing the same from rotating to an unlocked position.

When the closure members —4— and —5— are tightly closed stop member —20— will somewhat overlap on closure member —4— and prevent the loss of grain when the closure members are in a closed position.

When mounting the end-gate of my invention into operative position nut —21— is

released permitting the frame or brace member composed of boards —22— and —23— hingedly connected by hinge —24—, to be hingedly broken in which position the end-gate is inserted between upright lugs —25— and —26— on one side and —27— and —28— on the other side of the rear end of a wagon bed designated by numerals —29— and —30— on corresponding sides; and after the upright hinge pins —31— and —32— are snugly adjusted between said cleats then nut —21— is screwed up tight after brace member —33— is slipped over bolt —34—, thus holding the end-gate to operative position.

When closing closure members —4— and —5—, the operator will push in on each closure member toward the closed position causing latch member —1—, which is pivotally mounted on pivot pin —3—, to slidably move over supporting bracket —13— toward its position of rest where tongue —12— of latch member —1— is engaged behind keeper —8—. As closure members —4— and —5— rotate to closed position, guide bracket —9— guides the latch —1— to its closed position where it rests upon supporting bracket —2— and is locked in its closed position by lock member —10— as described.

To those who are skilled in the art to which this device pertains, it will be evident that certain minor changes may be made in the details of this device and still stay within the spirit and scope of this invention; but the preferred arrangement has been hereinabove described and illustrated in the drawings.

Having thus described the nature of my invention, what I claim as new and useful and desire to secure by Letters Patent is:

1. In a grain dumping end gate of the character described having a frame member with upright hinge pins and a pair of closure members, a lock member comprising in cooperative combination, a sliding latch, a bracket supported on one of said closure

members for the pivotal support of said latch nearer one end than the other, a bracket support for said latch on the other of said closure members; a limiting bracket for providing a predetermined open limit for said closure members; said latch member comprising an angle bar having an upright and a horizontal face, said horizontal face turned up at each end; a pivotally mounted lock member for said latch positioned at one end thereof and secured to said pivot mounting bracket, an engaging bracket member for slidably engaging the end of said latch member opposite said lock member; whereby said closure members may be securely held together to prevent loss of grain in wagons and when opened held into a predetermined open limit.

2. In a grain control end gate of the character described having a frame member and a pair of closure members hingedly connected therewith, a latch comprising in combination, a latch member pivotally mounted adjacent the free end of one of said closure members, a pivot supporting bracket therefor on said closure member, a bracket for slidably supporting said latch member secured to the other of said closure members and adapted to guide and support the free end of said latch member, a cooperating guide bracket on said latter closure member, positioned to hold said latch member in constant slidable engagement with said closure member; said latch member provided at each end with an integral tongue for a latch and a turned up flange as a stop member; pivoted lock means for holding said latch member in locked position; whereby said latch member may securely hold said closure members within a predetermined optional position of adjustment for the control of the release of grain from a wagon to which it is adapted to be secured.

In witness whereof, I hereunto set my hand this 31 day of May, A. D. 1926.

WILLIAM A. ORENDOFF,
